ABSTRACT OF THE DISCLOSURE

The compounds, 19-nor-7 α -methyl, 18-hydrogen or methyl-20-spiro-4,14-dien-3-one and the corresponding 19-nor-spiro-lactones are provided, prepared from the corresponding 19-nor-3-oxo-spiro-4,14-dienes. The compounds are useful as orally-effective antiestrogens and are also anabolic agents having low androgenicity.

SUMMARY OF THE INVENTION

This application is a continuation-in-part application of U.S. Ser. No. 67,615 filed Aug. 27, 1970, now abandoned.

The compounds of the present invention are 19-nor-7 α -methyl, 18-hydrogen or methyl-20-spirox-4-en-3-ones and the corresponding spirolactones which possess a high anabolic/androgenic ratio. This high anabolic/androgenic ratio is surprising, in light of the prior art teachings of other compounds in the series. In addition, the compounds possess a potent antiestrogen effect and are orally active as antiestrogens or as anabolic compounds. This latter high oral activity in the spiroxene series has heretofore been relatively low. The specific utility of these compounds is to antagonize the uterine growth stimulating activity of estrone and compounds of estrone-like activity. A further use is as anabolic compounds in animals and humans.

SUMMARY OF THE PRIOR ART

Spiroxenones are generally described in U.S. Pat. 3,254,074. The compounds in that patent are 4-en compounds which have activity as aldosterone inhibitors.

SPECIFIC EMBODIMENTS OF THE INVENTION

The compounds of this invention can be represented by the following formula:

in which R is

R' is CH_3 , and R'' is CH_3 or C_2H_5 . A preferred group of compounds are those in which R is $-CH_2-$, R' is CH_3 , and

2

R'' is CH_3 or C_2H_5 . An even more preferred compound is that in which R is $-CH_2-$, R'' is CH_3 , and R' is CH_3 . Another preferred compound is that in which R is

$$-\text{C}=\text{O}$$

and R' is CH_3 . These compounds can be prepared using the following reaction synthesis, diagrammed in Flow 10 Sheet I.

FLOW SHEET I

The reaction scheme starts from the known 3-methoxy 17-ketals of estrone or 7α -methyl estrone, Compound A. When R'' in Compound A is ethyl, the starting materials can be easily prepared using preparations and procedures available in the literature. An example is given supra of this preparation. The chosen Compound A is first brominated at position 16 using pyridinium bromide perbromide. In general, the bromination reaction takes place in an inert organic solvent at low temperatures (0° – 25° C.). The estrone ether and the perbromide are employed in approximately equimolar amounts.

In the next step of the reaction, the 16-bromo derivative (B) is dehydrobrominated to the Δ^{15} Compound C. This dehydrobromination reaction is effected by refluxing in a high boiling solvent (i.e., about 120 – 200° C.) in the presence of an alkali metal alkoxide, e.g., potassium-t-butoxide. The mixture is refluxed for several hours, cooled, and the product extracted with an aromatic hydrocarbon. After evaporation and recrystallization, the product C is recovered.

In the third step, the 17,17-ethylene dioxy group of C is transformed to the 17-keto derivative D, by means of dilute acid, such as p-toluenesulfonic acid, in an aqueous-organic solvent mixture. The organic solvent is preferably acetone. The product D is recovered after concentration and filtration.

Compound D is then converted to the 17-acetoxy-1,3,5(10),14,16-pentaene derivative E by treatment with p-toluenesulfonic acid and acetic anhydride. The pentaene E is then reduced to the tetraenoic-17-ol, Compound F. The reduction conditions utilize sodium borohydride in aqueous alcohol, preferably methanol or ethanol. Excess hydride is neutralized by the addition of acid such as glacial acetic acid. The product (F) is recovered by the concentration of organic solvent extracts.

The alcohol group at 17 of Compound F is then selectively oxidized to the 17-keto derivative (G). A suitable oxidation system is a dipyridine-chromium VI complex in a solvent such as methylene chloride. The oxidation proceeds rapidly at room temperature.

Compound G is then treated with allyl magnesium chloride in ether to yield the 17β-hydroxy-17α-allyl, Compound H. The reaction proceeds within 1–2 hours or less at room temperature. The 17α-allyl substituent is transformed to the 17α-(3'-hydroxypropyl)-17β-hydroxy, Compound J. An excess of borane in an organic solvent (suitably tetrahydrofuran) in the presence of 2-methyl-2-butene is first employed at low temperatures (-20° to

0° C.). The reaction mixture is then made basic, suitable with NaOH; then hydrogen peroxide is added and the mixture allowed to stand 8–12 hours at room temperature. The product, Compound J, is a key intermediate. By reference to the Flow Sheet, it can be seen that it can be treated following at least two separate processes to yield the desired $\Delta^{4,14}$ -spiroxenone (Compound I).

The first process of reaction, Compound J, is a three-step procedure via Compounds K and M. The first step, yielding Compound K, is a Birch reduction using metallic lithium and t-butanol in a solvent mixture of liquid ammonia and diethyl ether. After refluxing for 3–4 hours, the product K is separated and suspended in alcohol. The suspension is acidified with HCl and stirred at room temperature. After about 20–24 hours, the mixture is neutralized and the product, Compound M, recovered. The final step is the ring closure of the spiroxa ring using p-toluene sulfonyl chloride or methane sulfonyl chloride in pyridine. When the lactone

is desired, a ring closing oxidizing agent, e.g., chromic acid in acetone, is used.

Alternatively, Compound Q can first be converted to the spiroxene by closing the 17β -hydroxy- 17α -(3'-hydroxypropyl) substituents using p-toluene sulfonyl chloride in pyridine or chromic acid in acetone, followed by the Birch reduction and acid-catalyzed hydrolysis or ring closing oxidizing agent to yield the final desired $\Delta^{4,14}$ -spiroxenone, Compound I.

Although the above reaction sequence is illustrated using the 3-methoxy ether of the starting compound, other loweralkoxy compounds could be used with equal success. Loweralkoxy is used to mean all alkoxy groups having 1–6 carbon atoms.

The 7α -methyl-spiroxene compounds of the invention having a high anabolic/androgenic ratio are useful when it is desired to increase body weight and build muscle tissue without stimulating an androgenic response.

It will be apparent to one skilled in the art that the 18-CH_3 compounds prepared by total synthesis are d,l-isomeric mixtures. The d-isomer can be separated by the usual isolation techniques; alternatively, it can be prepared from d-isomeric intermediate compounds described in the literature.

The invention is further illustrated by means of the following examples, but it is not to be considered as limited thereto.

PREPARATIVE EXAMPLE

19-nor-7 α -methyl-20-spirox-4,14-dien-18-methyl-3-one

The starting material for this example is 19-nor- 7α -methyl - 18 - methyl - pregra-4-en-17 β -ol-3-one, which is described in J. Med. Chem. 9, 782 (1966). The processes are all as usually used and known to those skilled in the art. In addition, the final product is described in Great Britain Pat. 1,143,437 (1969). The analogous starting material for the 7α -non-substituted compound is also disclosed in J. Med. Chem. 9, 782 (1966) and is employed in these same reactions, in the same fashion.

STEP A

EXAMPLE 3

3-methoxy-7 α -methyl-estra-1,3,5(10),15-tetraene-17-one

A solution of 10 g. (0.031 mole) of the ketal prepared in Example 2 and 500 mg. of p-toluene sulfonic acid hydrate in a mixture of 750 ml. of acetone and 125 ml. of water is stirred at room temperature for 105 minutes. It is then treated with 800 mg. of sodium bicarbonate. After concentration of the mixture under reduced pressure to about one-half of its original volume it is diluted with one liter of saturated sodium chloride solution. The separated product is isolated by filtration, washed well with water and then dried. Recrystallization from 900 ml. of heptane yields 3 - methoxy-7 α -methyl-estra-1,3,5-(10),15-tetraene-17-one.

EXAMPLE 4

17-acetoxy-3-methoxy-7 α -methyl-estra-1,3,5(10),14,16-pentaene

To a solution of 690 mg. (2.44 mmoles) of the enone prepared in Example 3 in 20 ml. of acetic anhydride is added 120 mg. of p-toluene sulfonic acid. The mixture is stirred at room temperature overnight and then concentrated under reduced pressure (100 mm.) at 90° to about one-third of its original volume. The remaining anhydride is removed by treatment with a saturated solution of sodium bicarbonate. The product is extracted into diethyl ether and worked up to give a crystalline, colored residue. Recrystallization from methanol gives the product, 17 - acetoxy - 3 - methoxy - 7 α -methyl-estra-1,3,5(10),14,16-pentaene.

EXAMPLE 5

3-methoxy-7 α -methyl-estra-1,3,5(10),14-tetraene-17 β -ol

To a solution of 1.367 g. (4.2 mmoles) of the enol acetate prepared in Example 4 in 75 ml. of ethanol is added at 0° a solution of 825 mg. of sodium borohydride in 75 ml. of ethanol-water (10:3). The mixture is kept at 5-10° for 16 hours and then at room temperature for 4 hours. Glacial acetic acid is added to neutralize the excess hydride and the resulting mixture concentrated to near dryness under reduced pressure. The residue is extracted with ethylacetate and the resulting extract is washed, dried and concentrated to give a glass which crystallized on trituration with alcohol. Recrystallization from isopropanol yields the product, 3-methoxy-7 α -methyl-estra-1,3,5(10),14-tetraen-17 β -ol.

EXAMPLE 6

3-methoxy-7 α -methyl-estra-1,3,5(10),14-tetraen-17-one

A solution of 9.3 g. (0.0328 mole) of 3-methoxy-7 α -methyl-estra-1,3,5(10),14-tetraen-17 β -ol prepared as in Example 5 in 300 ml. of methylene chloride is added at a rapid dropwise rate to a stirred suspension of 46.5 g. (0.18 mole) of dipyridine-chromium (VI) complex in 800 ml. of methylene chloride at room temperature. The mixture is stirred 45 minutes and then filtered. The residue is washed with ethyl acetate and the organic layers are combined. Water is added to the filtrates and sufficient ethyl acetate is added to make the organic layer less dense than water. After the organic layer is washed with water, it is dried over sodium sulfate and concentrated to leave ~10 g. of crystalline residue. Recrystallization from methanol gives the desired 3-methoxy-7 α -methyl-estra-1,3,5(10),14-tetraen-17-one.

EXAMPLE 7

3-methoxy-7 α -methyl-estra-1,3,5(10),14-tetraen-17 α -allyl-17 β -ol

5.3 g. of the steroid prepared in Example 6 is dissolved in 268 ml. of diethyl ether and cooled to 0° C. 150 ml. of 3 M allylmagnesium chloride in tetrahydrofuran is added and the mixture stirred at room temperature for one hour. The solution is quenched with ammonium chloride and extracted with ethyl acetate, then washed with

water. After drying and evaporating, a yellow oil is obtained. Recrystallization from methanol yields a white crystalline solid, 3-methoxy-7 α -methyl-estra-1,3,5(10),14-tetraen-17 α -allyl-17 β -ol.

EXAMPLE 8

3-methoxy-7 α -methyl-estra-1,3,5(10),14-tetraen-17 α -3'-hydroxypropyl-17 β -ol

A dry flask under N₂ atmosphere is prepared for reaction by adding 14 ml. of 1 M diborane (20% excess) in 14 ml. distilled tetrahydrofuran. The vessel and contents are cooled to -20° C. and 5 ml. of 2-methyl-2-butene in 5 ml. of tetrahydrofuran is added and stirred for 1/2 hour. The temperature is maintained at -20° C. To the flask is added 4.0 g. of the allylic alcohol steroid prepared in Example 7 in 20 ml. of tetrahydrofuran. The flask is stirred at 0° C. for two hours. After cooling to -20° C., 14 ml. of 3 N NaOH is added slowly. The reaction mixture foams and when foaming ceases, 14 ml. of 30% aqueous H₂O₂ is added. The mixture is allowed to stand overnight at room temperature. The reaction is quenched by dilution with water and the tetrahydrofuran is evaporated under vacuum. The residue is crystallized, filtered, and purified. The product, 3-methoxy-7 α -methyl-estra-1,3,5(10),14-tetraen-17 α -(3'-hydroxypropyl)-17 β -ol is recovered and used in the next step without further identification.

EXAMPLE 9

3-methoxy-7 α -methyl-estra-2,5(10),14-trien-17 α -(3'-hydroxypropyl)-17 β -ol

To a dry flask equipped with a Dry Ice condenser and magnetic stirrer device under a N₂ atmosphere is added 0.5 g. of the steroid (prepared in Example 8) suspended in 7 ml. of t-butanol and 7 ml. of diethyl ether. 20 ml. of anhydrous liquid ammonia is added to the flask. Sufficient solid lithium wire is then added to turn the solution dark blue. The mixture is refluxed for 3-4 hours. Methanol is added to quench the reaction and the ammonia allowed to evaporate overnight under the N₂ stream. At this point, 25 ml. of water and 25 ml. of diethyl ether is added to the reaction flask. The mixture is extracted with methylene chloride, washed with water, dried and evaporated. A white crystalline powder is recrystallized from methanol and identified as 3-methoxy-7 α -methyl-estra-2,5(10),14-trien-17 α -(3'-hydroxypropyl)-17 β -ol.

EXAMPLE 10

7 α -methyl-estra-4,14-dien-17 α -(3'-hydroxypropyl)-17 β -ol-3-one

100 mg. of the powder prepared in Example 9 is suspended in 3.3 ml. of ethanol in a separate reaction flask. 0.4 ml. of a 2.5 N hydrochloric acid solution is then added and the reaction stirred at room temperature. After 24 hours, it is neutralized with aqueous sodium bicarbonate. The ethanol is removed by evaporation and the residue is crystallized, filtered, and dried, and the product was identified as 7 α -methyl-estra-4,14-dien-17 α -(3'-hydroxypropyl)-17 β -ol-3-one, M.P. 185-187° C.

EXAMPLE 11

7 α -methyl-19-nor-20-spiroxa-4,14-dien-3-one

820 mg. of the diol prepared in Example 10 is dissolved in 8 cc. of pyridine and cooled to 0° C. To this solution is added 820 mg. of p-toluene sulfonyl chloride and the mixture stirred at room temperature overnight. The solution is diluted slowly with water and an oily substance separates. This oil, after extraction with ethyl acetate and washing with water, is dried and evaporated to yield a dark oil. The oil is purified by thin layer chromatography on a silica gel with a 2% methanol/chloroform eluant. The product is taken up in benzene and recrystallized from a 10% ethanol/benzene mixture to give the product, 7 α -methyl-19-nor-20-spiroxa-4,14-dien-3-one.

5

A 10% solution of the 17-hydroxy steroid in 1:1 acetic anhydride:pyridine when allowed to stand 18 hours at 25° gives the corresponding 17-acetate, on concentration to dryness and crystallization from aqueous methanol.

STEP B

A 5% solution of the steroid in a mixture of 5:1 methanol:trimethylorthoformate is treated at 0° with 2,4-dinitrobenzene sulfonic acid (0.1 weight of steroid). After 20 minutes at 0° an excess of pyridine is added and the product enol ether is isolated after addition of water.

STEP C

The enol ether (5% in acetone) is treated sequentially at 0° with one equivalent of sodium acetate (5% in water), one equivalent of N-bromosuccinimide and a slight excess of glacial acetic acid. The mixture is then stirred 2 hours at 0° and treated with aqueous potassium iodide solution. The product is extracted into ether, washed with sodium thiosulfate solution, then water and finally dried over sodium sulfate. The solution is concentrated and the residue dissolved in acetone (~10%). The solution is then treated at 35° with concentrated hydrochloric acid. After 40 minutes at 35°, the mixture is allowed to stand at room temperature for 3 hours. The mixture, partially concentrated, is treated with water and extracted with ethyl acetate. The organic layer gives a dark residue which is chromatographed on alumina to afford the desired sterol 17-acetate.

STEP D

A suspension of the 3-hydroxy steroid in methanol-chloroform is treated sequentially with an equal weight of potassium carbonate (30% in water) and an equal weight of dimethyl sulfate. After 2 hours, additional carbonate and dimethylsulfate are added in the same amounts. After one hour, the mixture is partially concentrated and the product precipitated by addition of water. Saponification is completed by refluxing a 5% methanolic sodium hydroxide for 20 minutes. Concentration, then water addition gives the product 17-hydroxy steroid isolated by filtration.

6

STEP E

A 5% solution of the steroid in acetone is treated with 8 N chromic acid solution until the red color of the oxidant persists for one minute. Water is added and the mixture partially concentrated. The product is worked up in ether to give the desired ketone which can be recrystallized from aqueous methanol.

STEP F

A mixture comprised of the steroid, ethylene glycol toluene-sulfonic acid and benzene (ratio 1:1:0.1:25) is refluxed with water separation for 8 hours. The solution is cooled and treated with excess sodium bicarbonate solution. The organic layer is washed with water and then saturated sodium chloride. After drying and concentration, the ketal is isolated as a crystalline solid.

EXAMPLE 1

16-bromo-17,17-ethylenedioxy-3-methoxy-7 α -methyl-estra-1,3,5(10)-triene

To a solution of 34 g. (0.104 mole) of the 17-ethylene ketal of 7 α -methyl estrone methyl ether in 1100 ml. of tetrahydrofuran is added with stirring at 0°, 35.5 g. (0.11 mole) of pyridinium bromide perbromide in portions over five minutes. The mixture is stirred at 0° for one hour, the orange bromine color being replaced by yellow. The insoluble material is removed by filtration and the filtrate is concentrated to about 100 ml. It is then added to an excess of 5% sodium bicarbonate solution with stirring. The separated product is isolated by filtration and washed well with water. After drying under reduced pressure, the solid is recrystallized from ethyl acetate, and identified as 16-bromo-17,17-ethylenedioxy-3-methoxy-7 α -methyl-estra-1,3,5(10)-triene.

EXAMPLE 2

17,17-ethylenedioxy-3-methoxy-7 α -methyl-estra-1,3,5(10),15-tetraene

A suspension of 113 g. of freshly prepared potassium t-butoxide in 1500 ml. of xylene is heated until 250 ml. of the solvent is removed. The bromoketal prepared in Example 1 (32.3 g., 0.079 mole) is added and the mixture refluxed under nitrogen for 18 hours. After cooling to room temperature 500 g. of ice is added to the reaction mixture. The phases are separated and the aqueous phase extracted with benzene. The combined organic phases are washed well with water, then with saturated sodium chloride solution and dried. Concentration gives a pink crystalline residue which on separation from ethanol yields a solid crystalline steroid identified as 17,17-ethylenedioxy-3-methoxy-7 α -methyl-estra-1,3,5(10),15-tetraene.

EXAMPLE 12

3-methoxy-19-nor-20-spiroxa-7 α -methyl-1,3,5(10),14-tetraene

800 mg. of the diol prepared in Example 8 is dissolved in 8 cc. of pyridine and cooled to 0° C. To this solution is added 800 mg. of p-toluene sulfonyl chloride and the mixture stirred at room temperature overnight. The solution is then diluted with water. The crude product is recovered as an oil, which after purification and recrystallization, is identified as 3-methoxy-19-nor-20-spiroxa-7 α -methyl-1,3,5(10),14-tetraene.

EXAMPLE 13

7 α -methyl-19-nor-20-spiroxa-4,14-dien-3-one

The product prepared in Example 12 is treated with anhydrous ammonia and solid lithium in t-butanol following the procedure of Example 9. The product obtained is 19-nor-20-spiroxa-4-methoxy-7 α -methyl-2,5(10),14-triene. This latter product is then treated with acid following the procedure of Example 10 to yield the 7 α -methyl-19-nor-20-spiroxa-4,14-dien-3-one final product.

EXAMPLE 14

7 α -methyl-19-nor-20-spiroxa-4,14-dien-3,21-dione

A solution of 0.500 g. of the product prepared in Example 10, 7 α -methyl-estra-4,14-dien-17 α -(3'-hydroxypropyl)-17 β -ol-3-one, in 30 ml. of acetone is treated with 0.50 ml. of 8 N chromic acid at 10° C. The mixture is stirred 10 minutes and then diluted with chloroform and washed with water. Drying of the organic layer and concentration in vacuo gives the crude spirolactones. Recrystallization from ethyl acetate gives pure 7 α -methyl-19-nor-20-spiroxa-4,14-dien-3,21-dione.

When the product prepared in Example 8, 3-methoxy-7 α -methyl-estra-1,3,5(10),14-tetraen-17 α -(3'-hydroxypropyl)-17 β -ol, is treated as above with chromic acid in acetone, the product 3-methoxy-7 α -methyl-20-spiroxa-1,3,5(10),14-tetraene-21-one is prepared.

EXAMPLE 15

19-nor-20-spiroxa-4,14-dien-3-one; 19-nor-20-spiroxa-4,14-dien-3,21-dione

These compounds are prepared using the processes of Examples 1-15 above. The starting material is the 17-ethylene ketal of estrone-3-methyl ether. Following the sequential treatment, the products 19-nor-20-spiroxa-4,14-dien-3-one and 19-nor-20-spiroxa-4,14-dien-3,21-dione are isolated and identified.

What is claimed is:

1. The process of preparing a compound having the following structure:

wherein R''' is loweralkyl, R'' is methyl or ethyl, and R' is hydrogen or methyl, which comprises

(a) reducing, using sodium borohydride in aqueous alcohol, a compound having the following structure

to yield the corresponding 1,3,5(10),14-tetraen-17-hydroxy compound, and

(b) selectively oxidizing the 17-OH group to the desired final product.

2. A compound having the formula

30 wherein R is either

R' is either H or CH₃, and R'' is methyl or ethyl.

- 35 3. The compound of claim 2 wherein R is —CH₂—.
4. The compound of claim 3 which is

50 R'' being either methyl or ethyl.

5. The compound of claim 2 wherein R'' is ethyl.
6. The compound of claim 5 which is a mixture of d,l-optically active isomers.
7. The d-stereoisomer of the compound of claim 5.
